ABSTRACT OF THE DISCLOSURE

This invention is directed to a release mechanism for a rod used in a coronagraph or any other type spring loaded device. The release mechanism makes use of a pivotal lever which is held in place by two separate electrically released pistons which are used in case one has a misfire, then the other can be fired. When one piston release is fired the pivotal lever pivots by the unfired piston and releases the spring loaded rod.

STATEMENT OF GOVERNMENT INTEREST

The invention described herein may be manufactured and used by or for the Government of the United States of America for governmental purposes without the payment of any royalties thereon or therefor.

BACKGROUND OF THE INVENTION

This invention relates to release mechanisms and more particularly to a release mechanism including two electrically fired release mechanisms such as squibs either of which may release the device held in place by the two electrically fired release mechanisms.

Heretofore, spring loaded rods and other devices have been held in place by a single release mechanism. If a device is held in place by a single release mechanism, and the single mechanism does not operate, then the device will not release. Such devices used for remote control such as electrically fired release mechanisms on satellites or rocket borne instruments will bring about a failure if the single release mechanism fails. Some release mechanisms are provided with two electrical control circuits connected with a single unit, however, the problem may not be entirely electrical and the device fails to release. Therefore, it is necessary that two different release mechanisms be used to avoid failure in the event one of the release mechanisms fails.

SUMMARY OF THE INVENTION

This invention is directed to a system which makes use of two separate electrically fired release mechanisms including movable pistons to hold a single spring loaded rod or any other movable device in place for release by remote control. A spring loaded rod is provided with a pivotably mounted somewhat T-shaped lever which holds the spring loaded rod in place by use of two separate electrically fired powder driven pistons or any other operable holding mechanisms. The pistons lie in front of the T-shaped lever to hold the rod in place for release by either of the electrically fired powder driven pistons. When either of the electrically fired pistons are released, the T-shaped lever pivots about the pivot point and moves around the piston that is not fired. In the event one piston does not release, the other piston may be released to insure release of the spring loaded rod. The invention provides a release mechanism which releases a spring loaded device regardless of which release piston is actuated. In the event one release piston does not function, the other one is available and can release the spring loaded device.

2

STATEMENT OF THE OBJECTS

It is therefore an object of the present invention to provide a double control release mechanism for releasing a spring loaded device by actuation of either control mechanism.

Another object is to provide a duo-control release mechanism which provides an increased reliability for release of a spring loaded device by remote control.

Still another object is to provide a simple release mechanism for providing increased reliability against failure of operation.

While still another object is to provide increased reliability against failure of a release mechanism with very little additional weight due to the increased reliability.

Other objects and advantages of the invention will hereinafter become more fully apparent from the following description of the drawing.

BRIEF DESCRIPTION OF THE DRAWINGS

FIG. 1 is a side view partially in section to more clearly illustrate some of the elements.

FIG. 2 is a top view partially in section to more clearly illustrate the relationship of some of the elements.

FIG. 3 is a rear view illustrating some of the elements.

DETAILED DESCRIPTION

Now referring to the drawings there is shown by illustration a release mechanism including a spring loaded rod 11 held in place by two separate members 12 and 13 such as separately fired squibs each including a powder driven piston 14. The squibs are held in place by a plate 20. The rod 11 is mounted for movement in a frame 15 which is shown in its simplest form since the release mechanism is the important element of concern. The electrically operated release mechanisms are mounted onto the frame in a separate housing 16 in spaced relationship such that the retractable pistons 14 operate in parallel relationship with each other and with the frame to which the release mechanisms are mounted.

The end of the rod which is held by the release mechanisms has a slot 17 therein for reception of a somewhat T-shaped lever 18. The lever is secured at once end to the rod by a pin 19 about which the lever is permitted to pivot. The pin 19 also secures a rod support 21 in place about the rod, the purpose of which will be explained later. The free end of the T-shaped lever is formed with a smooth surface which includes a slight indentation 23 near the ends of the T-end. The frame is provided with an aperture 24 of sufficient size for the end of the rod to pass and a slot 25 in cooperation with the aperture for passage of the T-shaped end of the lever. A spring 26 is illustrated as being assembled around the rod between the rod support 21 and the frame in order to force the rod outwardly when held in place and released by one of the release mechanisms. The support aids in aligning the rod and also acts as a stop when the rod has been extended the desired distance to the fixed support 28. The support has Teflon feet 27 thereon which aids the support in its movement on the frame.

In the operation of the release mechanism, the rod is forced back against the spring such that the forward face 22 of the T-shaped lever is beyond the frame. The retractable pistons are assembled such that the ends of the pistons are supported in their housing with the lower ends below the position of the T-shaped end of the lever and in front of face 22. The rod is permitted to move forward such that the T-shaped end of the lever is held behind the retractable pistons will hold the rod in place against the compressional force of the spring. The "loaded" rod is now in a retracted position and ready for release to its extended position for the desired use.

The retractable pistons are connected into separate electrical circuits such that an electrical current flow through each of the separate release mechanisms will permit or force the pistons to be retracted separately independently of each other.

For release of the rod, an electrical current is passed through one of the release mechanisms activating the squib thereby forcing the retractable piston to be retracted. Upon retraction, the pivotable lever will be freed by the retracted piston for movement relative thereto. Since the lever is positioned behind both retractable pistons, release by one retractable piston permits the lever to move over about its pivot such that the T-shaped end will be free of the piston which has not been retracted. Therefore, the spring will force the rod into its "unloaded" position.

Now let's suppose that the electrical circuit to release mechanism 12 is actuated and nothing happens, that is, for some reason the release piston is not retracted, then the rod is not released. Since release mechanism 13 is available, the electrical circuit to release mechanism 13 is actuated. Upon retraction, the T-shaped lever will be released and the rod will be forced into its desired position by spring action. Therefore, it is important to have separate release mechanisms as well as separate electrical circuits especially when the device is remotely controlled such as in a satellite or on a rocket flight.

The squibs used may be of any type in which the piston is normally in an extended position and when fired by an electrical discharge, the piston is retracted. Since the T-shaped lever is pivoted at the end, removed from the squibs, retraction of either squib permits the lever to move about its pivot sufficiently to pass the squib piston which has not been retracted. Therefore, the spring loaded rod will be released regardless of which piston is retracted. Since there are two squibs, a misfire of one squib will not be fatal unless, of course, both squibs do not fire. Thus, the arrangement shown will provide a system which should

work everytime by release of at least one of the retractable pistons holding the spring loaded rod in place.

The system has been described as useful for a spring loaded rod which is released to be moved into place. The system may be used for any device held in place by a release mechanism especially for remote control by a direct electrical connection or by a radio signal which actuates an electrical circuit which activates the release mechanism.

What is claimed and desired to be secured by Letters Patent of the United States is:

1. A release means for holding a spring loaded device in a contained position relative to a base and subsequently release said device for movement by the spring to a different position; which comprises, first and second release mechanisms positioned relative to each other in parallelism, each of said first and second release mechanisms including an extended movable piston, a T-shaped pivotable lever supported by said device, said extended movable pistons of said first and second release mechanisms cooperating with said T-shaped pivotable lever and with each other to position said device in a contained position, whereby actuation of either of said first or second release mechanisms to retract its piston will release said T-shaped lever and said device from its contained position.
2. A release means as claimed in claim 1; wherein, each of said release mechanisms has electrically operated means to retract its piston.
